[57] CLAIM

The ornamental design for a portable condiment dispenser, as shown and described.

DESCRIPTION

FIG. 1 is a front elevational view of a portable condiment dispenser showing my new design;

FIG. 2 is a left side elevational view thereof;

FIG. 3 is a top plan view thereof;

FIG. 4 is a rear elevational view thereof;

FIG. 5 is a fragmentary cross-sectional view taken along line 5—5 of FIG. 1; and

FIG. 6 is a front elevational view of a second embodiment of that shown in FIG. 1, the other views being similar to those shown in FIGS. 1-4.

The bottom of each embodiment is plain and unornamented. The rear of the embodiments illustrated in FIGS. 7 to 11 is the same as the rear of the embodiment illustrated in FIGS. 1 to 6.
